UNITED STATES PATENT OFFICE.

WILLIAM M. SCOTT, OF BERWYN, PENNSYLVANIA.

CIRCUIT-BREAKER.

1,138,800.

Specification of Letters Patent. Patented May 11, 1915.

Application filed January 31, 1912. Serial No. 674,546.

To all whom it may concern:

Be it known that I, WILLIAM M. SCOTT, a citizen of the United States, residing in Berwyn, in the county of Chester and State of Pennsylvania, have invented a new and useful Circuit-Breaker, of which the following is a specification.

My invention relates to electric switches, and more particularly to electric switches which are latched or locked in normal position and suitably controlled to unlatch or unlock them.

More particularly my invention relates to automatic circuit breakers.

My invention resides in an electric switch or circuit breaker and its tripping mechanism, and resides more particularly in means preventing the immediate actuation of the tripping mechanism, as a start delaying device of the character shown and described in Letters Patent of the United States No. 830,537, September 11, 1906.

It is the object of my invention to provide means whereby the advantages of a start delaying device of the character referred to may be obtained, without derangement of the same as by the effect of dust or other material. To this end I provide a start delaying device which is practically hermetically sealed against the outer air preventing dust or other undesirable material reaching the functioning parts of the start delaying device.

The invention herein described is also applicable to retarding devices in general.

My invention resides in the features hereinafter described and claimed.

For an illustration of one of the forms my invention may take, reference is to be had to the accompanying drawings, in which:

Figure 1 is a side elevational view of an automatic circuit breaker embodying my invention. Fig. 2 is a front elevational view of the same. Fig. 3 is a side elevational view, some parts in section, of a part of the tripping mechanism and associated start delaying device. Fig. 4 is a horizontal sectional view through the start delaying device with some of the attached parts shown in plan and also in substantially horizontal section. Fig. 5 is a front elevational view of the mechanism shown in Fig. 3, some parts being shown in vertical section.

Referring to the drawings, upon a base 1 of suitable insulating material, such as slate or marble, are secured the terminal blocks 2

and 3 of copper or other good conductor. Adapted to bridge and electrically connect these contacts 2 and 3 is the member 4 representing a laminated bridging member, the member 4 being secured upon the arm 5 pivoted to the housing 6 at 7. The arm 5 carries also the movable intermediate metallic shunt contact 8 and the movable carbon shunt contact 9 which engage respectively with the stationary shunt metallic contact 10 and the shunt carbon contact 11, these shunt contacts opening in succession after the bridging member 4 leaves contacts 2 and 3, the final arc taking place between the contacts 9 and 11.

Pivoted at 12 in the housing 6 is the operator's lever 13 having the usual grip or handle 14 and extending to the other side of the pivot 12 forming one link of a toggle. At 15 upon the lever 13 is pivoted a second toggle link 16 having a stop surface 17 adapted to engage the stop surface 18 upon the lever 13. The link 16 is pivoted at 19 to the toggle link 20 pivoted at 21 in the housing 6 which housing is secured upon the base 1. Also pivoted upon the pivot 19 is a short toggle link 22 pivoted at 23 to the lug 24 upon the arm 5 to which the bridging member 4 is secured. Freely and independently pivoted on the member 13 at 15 is the tripping lever 25 bearing against the roller 26 pivoted at 27. Also pivoted on 27 is the actuator 28 movable with which is the lever 29 carrying the projection or nose 30 adapted to engage and actuate the lever 25. The member 28 extends into the downward path of travel of the tail 31 on the armature lever 32 pivoted at 33, the armature 34 being secured at the end of the lever 32. Surrounding the lower contact 3 or the stud connecting therewith is the iron mass 35 having poles 36 adapted to attract the armature 34 when the current passing through the contact 3 or the stud leading thereto reaches a predetermined value. Independently of the armature lever 32 there is pivoted upon 33 the bifurcated lever 37 to each arm or leg of which is pivoted on the axis 38 an arm or rod 39 extending downwardly, these rods being secured at their lower ends to the cover of the start delaying device hereinafter described, and as shown in Fig. 5. The rod 40 by which the pull exerted by the armature 34 is transmitted to the movable sucker element later described, is pivoted at its upper end to the armature lever

32 concentrically with the pivot 38 but independently of the bifurcated lever 37. The lower end of the rod 40 is bifurcated at 41, 41, Fig. 5, these legs 41, 41 being pivoted at 42 to the horizontally extending levers 43 which at their right hand ends, Fig. 3, are secured upon the shaft or pivot 44. The levers 43 are disposed on opposite sides of the chamber 45 which is provided with the cap 46 at its right hand end, as viewed in Fig. 3. The cap 46 and the end of the chamber 45 form air-tight and dust-tight bearings for the shaft 44 which extends through the end of the chamber 45 just inside of the cap 46. Inside of the chamber 45 there is secured to the shaft 44 the lever 47 pivoted at its other end at 48 to the vertically extending member 49 integral with or secured to the member 50 upon which is pivoted the ring member 51 on the pivots 52, 52. At right angles to the pivotal axes 52, 52 is a second pivotal axis on which the movable sucker element 53 is pivoted at 54 to the ring member 51. The sucker element 53 is, therefore, supported upon the member 49 but it is connected thereto through two pivotal axes at right angles to each other, thus giving a universal or gimbals connection therewith. This allows the sucker element 53 to perfectly and nicely adjust itself with the stationary sucker element 55 whose upper surface is the active sucker surface of the stationary element, the member 53 having raised portions on its lower surface which are suitably finished or prepared as indicated at 56, the surfaces on the parts 56 engaging the surface of the member 55 as explained in prior U. S. Patent No. 861,611, July 30, 1907. The lower sucker element 55 is in the bottom of the main casing 57 which at its upper end has the outwardly extending flange 58 between which and the cover 59 is provided suitable packing ring or gasket 60, if desired. The cover 59 is internally screw-threaded at 61 to receive the screw-threaded ring 62, the flange 58 extending over the screw-threaded flange on the ring 62 and being rotatable relatively to the ring 62 and to the cover 59 by handle 63 attached to the cup or casing 57. By thus rotating the cup 57 which carries the relatively stationary sucker element, the amount of surface coacting between the stationary and movable sucker elements may be varied as and for the purposes described in said prior patent No. 861,611. The rods or members 39, heretofore referred to, are fastened at their lower ends to the cover 59 as shown in Fig. 5. Within the member 49 is a spiral spring 64, under compression, exerting a downward pressure upon the head 65 upon the member 66, thus thrusting against the member 53. By this means lost motion between the member 53 and the member 49 and the parts, as lever 47, etc., attached thereto, is prevented so as to maintain the calibration of the instrument, and any lost motion between these parts, though relatively slight, would enable the early movement or attraction of the armature 34 in taking up such lost motion to deliver a force in the nature of a hammer blow to the sucker element 53 tending to lift it or separate it from the stationary sucker element improperly, that is, before the overload or other electrical condition had existed for the desired time or for other degree of overload or other electrical condition to which the apparatus is intended to respond. The left ends of the levers 43, as viewed in Fig. 3, are connected by a pivotal shaft 67 to which is pivoted the lower end of the member 68 within which engages the rod 69 pivoted at 70 to the armature lever 32. Inside of the member 68 is the spring 71 under compression, tending to hold the pivots 70 and 67 separated and therefore holding lever 32 and levers 43 apart, thus further preventing lost motion between the armature 34 and the levers 43 and attached parts, as at pivots 38 and 42.

On opposite ends of a diameter of the cover 59 are provided the coaxial pivots 72 which engage in slots 73 in the stirrup members 74 attached to the housing 6. These pivots 72 and slots 73 allow vertical adjustment of the cup 57 and attached parts for different initial or normal positions of the armature 34, which, as well understood, must be adjusted to different positions or different distances from the poles 36 so as to respond to different current strengths through the circuit breaker. This adjustment of the armature 34 for different electrical conditions to which the breaker is to respond is procured by the handle 75 which moves in a horizontal slot in the member 76 and carries at its inner end member 77 which has a projection 78. This projection 78 moves in an inclined slot in the member 78^a which member is rigidly attached to and forms part of the bifurcated lever 37 pivoted at 33. By moving this handle 75 in one direction or the other in its horizontal slot the projection 78 moves correspondingly in the inclined slot in member 78^a which slot slants upwardly and downwardly, the member 78^a and, therefore, the lever 37, is moved upon its pivot 33 and in so doing raises or lowers the rods 39 thus raising or lowering the start delaying device as a whole. This also adjusts the armature 34 to different distances from the poles 36, so that the breaker shall respond to different electrical conditions for which the armature 34 may be set. The construction is such that both the armature 34 and the lever 37 are moved to like or proportional extents, so that for whatever adjustment of the armature 34 for different load or electrical conditions the start delaying device as

a whole moves with it, so that there shall be no relative movement which would otherwise separate the sucker elements or prevent their proper coaction.

5. What I claim is:

1. The combination with electro-responsive means having a movable member, of relatively fixed and movable sucker elements normally in adhesive contact with each other, a positive jointed mechanical connection between said movable member of said electro-responsive means and said movable sucker element, and means acting between said movable sucker element and said movable member through said jointed connection to hold the same at maximum distance from each other while said sucker elements are in contact with each other, whereby said movable member is prevented from moving in advance of said sucker element due to lost motion in said jointed connection and premature separation of said sucker elements is prevented.

2. The combination with electro-responsive means having a movable member, of relatively fixed and movable sucker elements normally in adhesive contact with each other, a gimbal connection between the movable member of said electro-responsive means and said movable sucker element, and a spring thrusting against said movable sucker element and the remote element of said gimbal connection, whereby less than predetermined force applied to said movable member is prevented from separating said sucker elements by advance movement due to lost motion in said gimbal connection.

3. The combination with electro-responsive means having a movable member, of a sucker comprising relatively fixed and movable elements normally in adhesive contact with each other, a hollow member, a gimbal connection between said hollow member and said movable sucker element, a pivoted connection between said hollow member and the movable member of said electro-responsive means, and a spring within said hollow member thrusting against said hollow member and said movable sucker element, whereby less than pre-determined force applied to said hollow member is prevented from separating said sucker elements by advance movement due to lost motion in said gimbal connection.

4. The combination with electro-responsive means having a movable member, a sucker comprising relatively fixed and movable elements normally in adhesive contact with each other, a housing closed to the atmosphere inclosing said sucker, said fixed sucker element being in fixed relation with respect to said housing, means for adjusting said housing and said movable member of said electro-responsive means in definite relation with respect to each other, and a con-

nnection from said movable member of said electro-responsive means through a wall of said housing to said movable sucker element.

5. The combination with electro-responsive means having a movable member, of a sucker comprising relatively fixed and movable elements normally in adhesive contact with each other, a movable housing closed to the atmosphere inclosing said sucker elements in fixed relation with respect to said fixed sucker element, a member extending through a wall of said housing, a pivoted connection outside of said housing between said member and said movable member of said electro-responsive means, a pivotal connection between said member and said movable sucker element within said housing, and means for taking up lost motion between the movable member of said electro-responsive means and said movable sucker element.

6. The combination with a movable element, of a sucker comprising relatively fixed and movable elements normally in adhesive contact with each other, a housing closed to the atmosphere inclosing said sucker, said housing comprising relatively rotatable cup and cover, said fixed sucker element being in fixed relation with said cup, and a pivot extending through a wall of said cover connecting said movable element to said movable sucker element, rotation of said cup with respect to said cover serving to adjust the coöperating areas of said sucker elements.

7. The combination with a movable element, of a sucker comprising relatively fixed and movable elements normally in adhesive contact with each other, a housing closed to the atmosphere inclosing said sucker, said housing comprising relatively rotatable cup and cover, said fixed sucker element being in fixed relation with said cup, a pivot extending through a wall of said cover connecting said movable element to said movable sucker element, rotation of said cup with respect to said cover serving to adjust the coöperating areas of said sucker elements, and means for adjusting the positions of said movable element and said housing in definite relation with respect to each other.

8. In apparatus of the character described, the combination with a movable member, of a sucker comprising relatively fixed and movable elements, a housing closed to the atmosphere inclosing said sucker, and a rock shaft connecting the movable sucker element to said movable member extending through a wall of said housing.

9. In apparatus of the character described, the combination with a movable member, of a sucker comprising relatively fixed and movable elements, a housing for

said sucker closed to the atmosphere and comprising a cup and cover, the fixed sucker element movable with said cup with respect to said cover, and a rock shaft extending through a wall of said cover and connecting said movable member to the movable sucker element.

10. In apparatus of the character described, the combination with a movable member, of a sucker comprising relatively fixed and movable elements, a housing for said sucker closed to the atmosphere and comprising a cup and a cover, the fixed sucker element being rotatable with said cup with respect to said cover, said movable sucker element remaining in fixed relation to said cover respecting rotation relative to said fixed sucker element, and means extending through a wall of said cover connecting said movable member with said movable sucker element.

11. In apparatus of the character described, the combination with a movable member, of a sucker comprising relatively fixed and movable elements, a housing closed to the atmosphere inclosing said sucker elements, and a pivot extending through a wall of said housing at right angles to the direction of movement of the movable sucker element connecting said movable sucker element with said movable member.

12. In apparatus of the character described, the combination with a movable element, of a sucker, a housing closed to the atmosphere inclosing said sucker, a shaft extending through the wall of said housing, a connection from the movable element of said sucker to said shaft within said housing, and a connection from said shaft to said movable element outside of said housing.

13. In apparatus of the character described, the combination with a movable element, of a sucker, a housing closed to the atmosphere inclosing said sucker, a member extending through the wall of said housing, a connection from the movable element of said sucker to said member within said housing, and a connection from said member to said movable element outside of said housing.

14. In apparatus of the character described, the combination with a movable element, of a sucker, a housing closed to the atmosphere inclosing said sucker, a member extending through the wall of said housing, a lever outside of said housing connected to said member and to said movable element, and a lever inside of said housing connected to said member and to the movable sucker element.

15. In apparatus of the character described, the combination with a movable element, of a sucker, a housing closed to the atmosphere inclosing said sucker, a rock

shaft extending through the wall of said housing, a lever secured to said rock shaft within said housing, the movable sucker element pivoted to said lever, and a lever secured to said rock shaft outside of said housing and connected to said movable element.

16. In apparatus of the character described, the combination with a movable element, of a sucker, a housing closed to the atmosphere inclosing said sucker, a rock shaft extending through the wall of said housing, a lever secured to said rock shaft within said housing, the movable sucker element pivoted to said lever, a lever connected to said rock shaft outside of said housing, and a member pivoted to said lever and to said movable element.

17. In apparatus of the character described, the combination with a movable element, of a sucker, a housing closed to the atmosphere inclosing said sucker, a rock shaft extending through the wall of said housing, a lever secured to said rock shaft within said housing, the movable sucker element pivoted to said lever, a lever connected to said rock shaft outside of said housing, a member pivoted to said lever and to said movable element, and means outside of said housing connected to said movable element and to said last-mentioned lever for preventing lost motion.

18. In apparatus of the character described, the combination with a movable element, of a sucker, a housing closed to the atmosphere inclosing said sucker, a rock shaft extending through the wall of said housing, a lever secured to said rock shaft within said housing, the movable sucker element pivoted to said lever, a lever connected to said rock shaft outside of said housing, a member pivoted to said lever and to said movable element, and a resilient connection outside of said housing between said last-named lever and said movable element for preventing lost motion.

19. In apparatus of the character described, the combination with a movable element, of a sucker, a housing closed to the atmosphere inclosing said sucker, a rock shaft extending through the wall of said housing, a lever secured to said rock shaft within said housing, the movable sucker element pivoted to said lever, a lever connected to said rock shaft outside of said housing, a member pivoted to said lever and to said movable element, a resilient connection outside of said housing between said last-named lever and said movable element for preventing lost motion, and means inside of said housing for taking up lost motion between the movable sucker element and said first-named lever.

20. In apparatus of the character described, a sucker comprising relatively fixed and movable elements normally in adhesive

contact with each other, a housing inclosing said sucker and comprising a cup and a cover, the relatively fixed sucker element being in fixed relation with said cup, and said 5 cup movable with respect to said cover for adjusting said sucker elements with respect to each other.

21. In apparatus of the character described, a sucker comprising relatively fixed 10 and movable elements, a housing inclosing said sucker elements and comprising a cup and a cover, said relatively fixed sucker element being in fixed relation with said cup, and a connection between said cup and cover 15 permitting rotation between said cup and said cover for adjusting said sucker elements with respect to each other comprising a member secured to said cover, and a flange on said cup intervening between said member 20 and said cover.

22. In apparatus of the character described, a sucker comprising relatively fixed and movable elements, a housing closed to the atmosphere inclosing said sucker elements 25 and comprising a cup and a cover, the relatively fixed sucker element being in fixed relation with said cup, a connection between said cup and cover permitting rotation of said cup with respect to said cover for adjusting said sucker elements with respect to 30 each other, and a mechanical connection from said movable sucker element through a substantially air tight joint in the wall of said cover.

35 23. In apparatus of the character described, the combination with a movable element, of a sucker comprising relatively fixed and stationary elements, a housing inclosing said sucker elements and comprising a cover 40 and a cup rotatable with respect to said cover, a shaft extending through the wall of said cover, a connection from the relatively movable sucker element to said shaft within said housing, and a connection from said shaft to said movable element outside of 45 said housing.

24. In apparatus of the character de-

scribed, the combination with a movable element, of a sucker comprising relatively fixed and movable sucker elements, a housing inclosing said sucker elements and comprising a cover and a cup rotatable with respect to said cover, a member extending through the wall of said cover, a lever outside of said housing connected to said member and to 50 said movable element, and a lever inside of said housing connected to said member and to the movable sucker element.

25. In apparatus of the character described, the combination with a movable element, of a sucker comprising relatively fixed and stationary elements, a housing inclosing said sucker elements and comprising a cover and a cup rotatable with respect to 55 said cover, a shaft extending through the wall of said cover, a connection from the relatively movable sucker element to said shaft within said housing, a connection from said shaft to said movable element outside of said housing, and means for simultaneously adjusting the position of said movable element and said housing.

26. In apparatus of the character described, the combination with a movable element, of a sucker comprising relatively fixed 75 and movable sucker elements, a housing inclosing said sucker elements and comprising a cover and a cup rotatable with respect to said cover, a member extending through the wall of said cover, a lever outside of said 80 housing connected to said member and to said movable element, a lever inside of said housing connected to said member and to the movable sucker element, and means for simultaneously adjusting the position of 85 said movable element and said housing.

In testimony whereof I have hereunto affixed my signature in the presence of the two subscribing witnesses.

WILLIAM M. SCOTT.
